(57) **CLAIM**

We claim the ornamental design for a mobile phone, as shown and described.

DESCRIPTION

FIG. 1 is a front perspective view of a first embodiment of a mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a second embodiment thereof;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a rear perspective view thereof.

The dot-dash broken lines and the evenly-spaced broken lines within the solid line showing, represent a boundary that forms no part of the claimed design.

The surfaces adjoining the outer perimeter solid lines shown as unshaded surfaces in the figures forms no part of the claimed design.

The remaining evenly-spaced broken lines in the figures depict portions of the mobile phone which form no part of the claimed design.

1 Claim, 12 Drawing Sheets
